UNITED STATES PATENT OFFICE.

DWIGHT D. KING, OF WARREN, PENNSYLVANIA.

DESIGN FOR A LAMP.

47,925.

Specification for Design.

Patented Oct. 5, 1915.

Application filed April 30, 1915. Serial No. 25,068. Term of patent 14 years.

To all whom it may concern:

Be it known that I, DWIGHT D. KING, a citizen of the United States, residing at Warren, in the county of Warren and State of Pennsylvania, have invented a new, original, and ornamental Design for Lamps, of which the following is a specification, reference being had to the accompanying drawing, forming a part thereof.

Figure 1 is a view in front elevation, showing my new design. Fig. 2 is a view in side elevation, and Fig. 3 is a view in rear elevation.

I claim:

The ornamental design for a lamp, as shown.

DWIGHT D. KING.

Witnesses:

B. K. ROGERS,

B. W. STERN.
